UNITED STATES PATENT OFFICE.

ROBERT M. DIXON, OF EAST ORANGE, NEW JERSEY, ASSIGNOR TO THE SAFETY CAR HEATING AND LIGHTING COMPANY, OF NEW JERSEY.

DESIGN FOR A REFLECTOR.

SPECIFICATION forming part of Design No. 23,560, dated August 14, 1894.

Application filed July 13, 1894. Serial No. 517,495. Term of patent 14 years.

To all whom it may concern:

Be it known that I, ROBERT M. DIXON, a resident of East Orange, county of Essex, State of New Jersey, have invented and produced a new and original Design for a Reflector, of which the following is a specification.

The essential feature of my design consists in a reflector, ovaloid in cross-section for a portion of its length and cylindrical in cross-section for the remainder of its length.

In the drawings—Figure 1 shows a side view of a reflector embodying my design; and Fig. 2 is a plan view thereof.

In the drawings, *a* is one end of the reflector which is ovaloid in cross-section. *b* is the other section of the reflector which is cylindrical in cross-section. These two sections *a* and *b* are united by an ogee curved section *c* by which one section is merged into the other.

What I claim is—

The design for a reflector, substantially as shown and described.

ROBERT M. DIXON.
